FLUORESCENT LIGHTING FIXTURE

Albert J. Michaud, Salem, Mass., assignor to Sylvania
Electric Products Inc., a corporation of Delaware

Filed Dec. 31, 1959, Ser. No. 58,880

Term of patent 14 years

(Cl. D48—23)

FIGURE 1 is a perspective view of a fluorescent lighting fixture showing my new design;

FIGURE 2 is an enlarged end view thereof with the end plate removed; and

FIGURE 3 is a reduced rear elevation thereof.

The dominant features of my design reside in the portions shown in full lines.

I claim:

The ornamental design for a fluorescent lighting fixture, as shown and described.
